UNITED STATES PATENT OFFICE.

CORYDON L. PRINDLE, OF EVANSTON, ILLINOIS.

GATE FOR SWING-BRIDGES.

SPECIFICATION forming part of Letters Patent No. 635,589, dated October 24, 1899.

Application filed July 5, 1899. Serial No. 722,805. (No model.)

To all whom it may concern:

Be it known that I, CORYDON L. PRINDLE, a citizen of the United States, residing at Evanston, in the county of Cook and State of Illinois, have invented a new and useful Improvement in Gates for Swing-Bridges, of which the following is a specification, reference being had to the accompanying drawings.

My invention relates more specifically to improvements in their application to swing-bridges of the vertically-swinging guards in common use at railroad street-crossings and already incorporated in certain bridge-gate patents and in improvements in the devices for their automatic operation, my aim being to provide a safety-gate that shall itself be safe in its operation and practical in actual use and combine as far as possible a maximum of utility with a minimum of interference with the use of the bridge. I attain this object by the mechanism illustrated in the accompanying drawings, in which—

Figure 1 is a front elevation of the bridge-abutment with the gate attached, the gate being shown on the right side as open and on the left as closed. Fig. 2 is a plan view of the abutment and gate, the bridge being shown as partly closed. Fig. 3 is a plan view of the end of the bridge, a part being cut away to show in detail the flange peculiar to my invention. Fig. 4 is a section on the line 4-4 in Fig. 2, the gate being in elevation, showing the parts of the mechanism on one side of the bridge in their relative positions when the bridge is closed and the gate open. Fig. 5 partially illustrates the various modifications that may be made in the combination of the gate-guard and actuating-lever; and Fig. 6 is a perspective view of the end of the abutment, showing the application of the gate to a bridge crossed by an elevated street-railway.

The gate proper in its usual form consists of the main guard C and pedestrian-guard D, attached to the upper surface b' of the abutment B, the guards extending horizontally at a suitable elevation across the abutment when the bridge is open and being elevated to a vertical unobstructing position when the bridge is closed. Pivotedly supported upon standards h', attached to the ledge b² of the abut-

ment, are arranged transverse levers H in approximately parallel lines, the lever usually having a horizontal curvature corresponding to that of the abutment and end of the bridge. 55 The lever has an upper surface consisting of the concave section h³, extending from near the fulcrum h² to the apex h⁵, and the convex section h⁴, extending from the apex to the free end of the lever. 60

A flange I is projected from and extends usually approximately across the end of the bridge A and at such elevation thereon that a right line corresponding to its base intersects the lever H at the points h⁹ and h¹⁰, Fig. 1, 65 when the lever is in the position shown with the bridge open and the gate closed. The flange usually has a part cut away from its outer edge on the side corresponding to the lever farthest from the edge of the abutment, 70 forming the indentation i², and from the inner edge at the opposite side, forming the aperture i¹.

A connecting-rod c h is pivotally attached at its upper extremity to the reverse projection c' of the main guard at c⁴ and at its lower extremity to the inner end h⁷ of the finger h⁶, projected from the side of the lever at h⁸. 75

It will be readily seen that in operation as the bridge is being closed from either side the flange I impinges and gradually depresses the lever H, which through the medium of the connecting-rod c h simultaneously elevates the main guard to the vertical position, the lever and guard gradually gravitating again to their original positions as the lever is released by the opening bridge, the gate being thus interposed again before the open draw. 85

The usual pedestrian-guard D protects the footway and in my invention rotates on the same axis c² as the main guard. The pedestrian-guard is elevated automatically by the main guard by means of the mechanism consisting of the vibrating lever g', pivoted at one end to the gate-standard at g³, the opposite end connecting pivotally at g⁵ with the lower extremities of two radiating arms g³ and g⁴, which are connected at their upper extremities with the main and pedestrian guards, respectively, at the pivotal points g⁸ 95 and g⁶. It will be seen that when the main guard is rotated from the horizontal to the 100

- vertical position it carries with it the arm g^4 , together with the jointly-pivoted arm g^3 , thereby simultaneously elevating the pedestrian-guard. As the pedestrian-guard when released returns to the horizontal position by its own weight and does not require to be forced down, the connection at g^6 is made to consist of a downwardly-extending slot d' and a sliding pivot, which admits of the guard being 5 partially raised by hand by pedestrians who are late in passing off the opening bridge or somewhat in advance of the closing bridge. The frequent convenience of this advantage will be obvious and may sometimes be of 10 great importance. Instead, however, of this automatic mechanism it may sometimes be preferable to provide the pedestrian-guard with a projecting arm and second connecting-rod corresponding to the equipment of the 15 main guard, the two connecting-rods jointly engaging the finger, the two guards being thus operated simultaneously by the lever, as shown in the surface gate in Fig. 6.
- In applying the gate to a bridge crossed by 20 an electric street-railway with overhead trolley-wires to avoid contact of the main guard with the trolley-line the guard is shortened sufficiently to admit of its passing under the wire and extended when in a horizontal position to the length required by means of the 25 trolley-section E. This angular device is attached pivotally to the free end of the main guard at e' and consists of a horizontal bar e^2 and vertical stanchion e^3 . A controlling-bar 30 e^f is pivoted at one extremity to the stanchion at e^4 , the other extremity being pivoted to the gate-standard F at f' . It will be readily seen that as the main guard is rotated the controlling-bar e^f will hold the bar e^2 in a 35 constantly horizontal position, thereby escaping contact with the trolley-wire. Incidentally the controlling-bar serves as an auxiliary guard and the stanchion for the usual supporting-pendant.
- The main guard is adjustably counterbalanced by the weight e^3 , which engages the screw-threaded arm c^5 of the guard by means 40 of a threaded perforation, and is readily adjusted as varying atmospheric and other conditions often require by being revolved into greater or less proximity to the fulcrum of the guard. The lever H is similarly counterbalanced by the weight h^{11} and threaded projection h^{12} and is usually somewhat over- 45 counterbalanced to effect its proper gravitation and with it the main guard when released by the flange. When desirable, the main-guard counterbalance may be embraced in the connecting-rod, but not adjustably, as 50 shown in the elevated gate in Fig. 6. It may also sometimes be preferable to adjust the guard and lever to counterbalance each other.
- Usually the main guard consists of two sections c^7 and c^8 , Fig. 2, united at the outer 55 ends with the trolley-section when the latter is used, the section c^7 having its bearing on the shore side of the supporting-standard and

carrying the counterbalance and the section c^8 on the river side and engaging the connecting-rod.

The distance of the pivotal point c^4 from the fulcrum c^2 of the main guard is proportionate to the fall of the lever at h^8 , being affected also somewhat by the relative direction of oscillation of the two extremities of 70 the connecting-rod, and the radii of the segments forming the convex and concave surfaces h^4 and h^3 are governed by the length of these surfaces relatively to the fall of the lever, each involving a problem of geometrical 75 solution, but readily determined by simple experiments.

It is obviously not imperative that the sections h^3 and h^4 shall be respectively concave and convex in form, but may be right lines 80 forming a vertically-convex contact-surface; but the convex form of the part of the lever traversed by the flange in the direction of the fulcrum and concave form in the opposite direction when the bridge is being closed and 85 the levers depressed and the reverse when the bridge is being opened and the levers released are important, as thereby the same inclination of the traversed surface to the plane of the flange is maintained at all points 90 and a consequent uniformity of speed in the rotation of the guard and of frictional resistance to the flange are secured.

The finger h^6 , attached to the lever that is actuated by the inner half of the flange I, will 100 require to be extended downward from the lever before being projected to the connecting-rod, as shown by h^{13} , Fig. 1, in order to 105 escape interference with the outer half of the flange. It will be seen that as each leaf of the flange is shortened at the end adjacent to the lever which it acts upon when the bridge is opened in the direction opposite to either 110 particular lever the flange will begin at once to release that lever, but when opened in the direction of the lever will not begin to release 115 it until the bridge begins to pass that side of the abutment with a corresponding action when the bridge is being closed, the result obtained being that the lowering or elevating 120 of the guard on either side of the abutment is as nearly as possible simultaneous with the opening or closing of the bridge, and consequently the greatest efficiency of the gate is secured with the least interference with the 125 transit use of the bridge.

It is preferable that the connecting-rod shall be provided with a tension-spring adjusted at any suitable point between its extremities, as shown in the elevated-railway 125 gate in Fig. 6, as thereby the otherwise necessary perfect adjustment between the guard and lever is avoided, sufficient rigidity of the guard is secured with a yielding facility sometimes important, the recoil of the spring starts 130 the downward gravitation of the guard, and too-sudden impulse of the guard is avoided both in starting and stopping.

Obviously the gate may be locked in the

upright position, and thus rendered inoperative when out of repair, and by making the connecting-rod readily detachable from the guard the guard may be lowered in front of 5 the closed bridge when the bridge is under repairs.

The gate may be as readily applied to an elevated street-railway as to a surface road, as illustrated in Fig. 6. The gate-guard and 10 lever being, one or both, counterbalanced or adjusted to counterbalance each other, and therefore requiring only friction to be overcome in operating them, there is scarcely a limit to the strength that may be given to the 15 gate. The guard at an elevated-railway drawbridge - crossing consisting of a single or trussed bar of iron or steel with equally strong supports can be made as strong as the abutment itself and capable of sustaining any 20 pressure or contact that the abutment would withstand. The simplicity of the entire mechanism is such that there is little liability to get out of order, and the gate once in position will require little further attention. Its value 25 as a guard before an open draw on an elevated road can hardly be overestimated, and the sense of security derived therefrom by street-car passengers is important even under a system in which accidents are supposed 30 to be unlikely to occur.

Obviously the gate may be made to consist of a single guard spanning the entire abutment and actuated by a single lever, and between such simple construction and the mechanism herein described there may be many 35 variations, as partially shown in Fig. 4, each involving essential features common to them all. It will be observed that when a single lever is used the gates, if in pairs on opposite 40 sides of the abutment, will be operated both together, but where two levers are used will be operated independently of each other. The choice between the different styles of construction will be governed by the size and 45 traffic importance of the bridge.

I am aware that many of the features described in clearly explaining my improvements are not original, some of them being common in more or less effective forms to several bridge-gate devices.

What I claim as new, and desire to secure by Letters Patent, is—

1. In a bridge-gate mechanism the independently-movable levers H provided with the 55 adjacent concave and convex sections h^3 and h^4 of the double-inclined traversed surface, said levers being pivotally attached at one extremity to the ledge of the bridge-abutment and engaging at approximately the opposite 60 extremity the connecting-rods ch , in combination with the independently-movable guards

C, said connecting-rods ch and the transverse flange I or an equivalent longitudinal projection of the bridge, substantially as and for the purpose specified. 65

2. In a bridge-gate mechanism the flange I, having the indentation i^2 at one extremity and the aperture i^3 at the opposite extremity, in combination with the bridge A and levers H, H, substantially as and for the purpose specified. 70

3. In a gate of the class described the mechanism consisting of the device E, having the horizontal section e^2 and vertical section e^3 , in combination with the controlling-bar e^f , 75 the guard C and standard F, substantially as and for the purpose specified.

4. In a gate of the class described the mechanism consisting of the vibrating lever g' , and radiating arms g^3 and g^4 , in combination with the standard F and guards C and D, substantially as and for the purpose specified. 80

5. In a bridge-gate mechanism the combination with the independently-movable guards C and connecting-rods ch , of transverse vertically-convex vertically-vibrating levers, independently disposed and pivotally mounted approximately at one extremity on the ledge of the abutment and engaging at approximately the opposite extremity means of connecting said levers with said guards, and actuated by a transverse horizontal flange or equivalent conformation of the end of the bridge, substantially as specified and shown. 85

6. A bridge-gate mechanism consisting of 95 the combination with vertically -swinging guards, connecting-rods, and a transverse actuating-flange or equivalent longitudinal projection of the bridge, of independently-disposed vertically - vibrating convex levers, 100 whereby the guards on the opposite sides of the abutment are independently operated, substantially as specified and shown.

7. A bridge-gate mechanism consisting of 105 the combination with vertically -swinging guards, connecting-rods and independently-disposed vertically-vibrating convex levers, of a transverse actuating-flange or equivalent conformation of the end of the bridge the inner and outer sections thereof being suitably 110 shortened at the ends adjacent to the levers to which they respectively appertain, whereby the independently-operated guards are actuated approximately simultaneously with the transit of the bridge on their respective 115 sides of the abutment, substantially as specified and shown.
